UNITED STATES PATENT OFFICE

ARTHUR STOCKSTROM, OF ST. LOUIS, MISSOURI, ASSIGNOR TO AMERICAN STOVE COMPANY, OF ST. LOUIS, MISSOURI, A CORPORATION OF NEW JERSEY

DESIGN FOR A RANGE

Application filed September 26, 1929. Serial No. 32,880. Term of patent 14 years.

To all whom it may concern:

Be it known that I, ARTHUR STOCKSTROM, a citizen of the United States, residing in the city of St. Louis, and State of Missouri, have invented a new, original, and ornamental Design for Ranges, of which the following is a specification, reference being had thereto in the accompanying drawings.

In the accompanying drawings Figure 1 is a perspective view of a range showing my new design, with the cover elevated.

Figure 2 is a perspective view of a range showing my new design with the cover closed.

I claim:

The ornamental design for a range, as shown and described.

In testimony whereof, I hereunto affix my signature.

ARTHUR STOCKSTROM.
